(57) **CLAIM**

The ornamental design for a writing instrument or stylus, as shown and described.

DESCRIPTION

FIG. 1 is a perspective view of an ornamental design for a writing instrument or stylus according to the present invention;

FIG. 2 is a front elevational view thereof;

FIG. 3 is a rear elevational view thereof;

FIG. 4 is a right side view thereof;

FIG. 5 is a left side view thereof;

FIG. 6 is a top view thereof; and,

FIG. 7 is a bottom view thereof rotated 180 degrees from FIG. 6.

All portions shown in broken lines are environmental and illustrative only and form no part of the claimed design.
